(57) CLAIM

The ornamental design for a money clip card holder wallet as shown and described.

DESCRIPTION

FIG. 1 is a perspective view of a money clip card holder wallet showing the claimed design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines in the drawings depict unclaimed subject matter that forms no part of the claimed design.
